UNITED STATES PATENT OFFICE.

SALOMON RIEGER, OF NEW YORK, N. Y.

DESIGN FOR A COMBINED RAZOR-STROP AND MIRROR.

43,020.

Specification for Design.

Patented Sept. 10, 1912.

Application filed July 12, 1912. Serial No. 709,073. Term of patent 7 years.

To all whom it may concern:

Be it known that I, SALOMON RIEGER, a subject of the Emperor of Russia, residing in the city of New York, borough of Brooklyn, in the county of Kings and State of New York, have invented a new, original, and ornamental Design for a Combined Razor-Strop and Mirror, of which the following is a specification, reference being had to the accompanying drawing, forming part thereof.

The figure is a perspective view of the combined razor strop and mirror, showing my design.

I claim:

The ornamental design for a combined razor strop and mirror, as shown.

SALOMON ^{his} RIEGER.
mark.
